DISPENSING CONTAINER

Hugh F. Kirkwood, York Village, Maine

Application December 29, 1944, Serial No. 570,351

7 Claims. (Cl. 222—260)

My invention relates to the packaging and handling of plastic materials such as shaving cream, shoe polish and the like, and has among its objects and advantages the provision of an improved dispensing container.

In the accompanying drawings:

Figure 1 is a side view of the invention.

Figure 2 is an enlarged sectional view along the line 2—2 of Figure 1.

Figure 3 is an enlarged sectional view along the line 3—3 of Figure 1.

Figure 4 is an enlarged sectional view along the line 4—4 of Figure 2.

Figure 5 is a fragmentary sectional view of a spring mount.

Figure 6 is an end view of a spring tensioning screw.

Figure 7 is a side view of the package containing part of the container as in the form purchased by the user.

Figure 8 is an enlarged sectional view along the line 8—8 of Figure 7, and

Figure 9 is an enlarged sectional view along the line 9—9 of Figure 7.

In the embodiment of the invention selected for illustration, Figures 7, 8 and 9 illustrate a package or tube structure 10 for containing the plastic material to be dispensed. This tube structure comprises a barrel 12 provided with a piston 14 in one end thereof. This piston is of hollow formation, as at 16, and the piston is provided with an open inner end 18. While the piston 14 slidably engages the inner face of the barrel 12, the piston is fitted sufficiently tight to offer considerable resistance against relative rotation.

The other end of the barrel 12 has a constricted neck 20 within which is fixedly mounted a nozzle body 22. This nozzle body is provided with a longitudinal bore 24 terminating short of the outer end of the body, as the latter appears in Figure 9. This bore is arranged coaxially of a larger bore 26 terminating in a valve seat 28. The body 24 is of smaller diameter than the barrel 12 to provide an annular space 30 between the barrel and the body down to the neck 20. Ports 32 are provided in the body 22 a short distance above the valve seat 28 to establish communication between the bore 26 and the space 30.

The container or barrel 12 is made of a plastic material possessing sufficient elasticity to maintain its wall in snug contact with the piston 14, whereby to establish a leakproof contact between the piston and the container or barrel without the use of piston rings.

The body 22 is provided with a circumferential

groove 34 a short distance inwardly of its outer end to weaken the body in a plane intersecting the bore 22. Thus the end portion 36 of the body may be broken off to convert the body into a nozzle structure. The piston 14 is provided with a stem 38 provided with a short bore 40 having communication with the cavity 16 in the piston 14. This stem is also weakened at 42 to facilitate breaking of the stem in a plane intersecting the bore 40. Figure 7 illustrates the tube structure 10 intact, this being the form of the tube structure as it is purchased by the user for placement in the extruding device coating with the tube structure and forming a part of the invention. However, the tube structure is also intended to be sold as a unit with the extruding structure.

The extruding structure comprises an outer barrel 44 within which the barrel 12 is contained. An annular shoulder 46 is formed at one end of the barrel 44 to constitute a rest for a washer 48 fitting snugly on the neck 20. The neck 20 fits loosely in a neck 50 adjacent the annular shoulder 46, and a tip cap 52 is slipped on the neck 50 and frictionally connected therewith. This tip includes an end bore 54 through which the body or nozzle 22 is projected.

The other end of the barrel 44 is threadedly connected at 56 with a cap 58 having an annular shoulder 60 constituting a rest for a washer 62 interposed between the shoulder and the flared end 64 of the tube 12. The opening 66 in the washer 62 is of sufficient diameter to accommodate the piston 14, the latter projecting partly outside the tube 12 in the full condition of the latter.

A feed screw 68 is arranged longitudinally inside the tube 12 and extends loosely through the bore 40 in the piston 14, but the screw has unthreaded relation with the piston. One end of the feed screw is provided with a rounded end 70 constituting a valve having normal seating engagement with the seat 28. The other end of the feed screw is provided with a head 72 lying inside a spring housing 74. This housing is provided with coaxial bores 76 and 78, the bore 76 being of smaller diameter and provided with longitudinal grooves 80 for slidably containing lugs 82 on the head 72.

The screw 68 extends through a bore 84 in a wall 86 at one end of the spring housing 74, with the head 72 lying against the inner face of the wall. A lock nut 88 is threadedly connected with the feed screw 68 and engages the outer face of the wall 86 to fixedly connect the feed screw with the spring housing 74.

The cap 58 includes a bore 90 within which the spring housing 74 is rotatably supported. This cap includes an annular shoulder 92 constituting a rest for a washer 94 clamped between the shoulder and an annular flange 96 at the inner end of the spring housing 74. All the washers 48, 62 and 94 are of a resilient nature, but the washers 48 and 62 are of sufficient rigidity to withstand the pressures applied thereto without yielding in an objectionable degree.

Inside the spring housing 74 is mounted a compression spring 98, this spring having one end attached in a groove 100 in the head 72 and its other end abutting a wall 102 at the outer end of the spring housing.

A body 104 is threadedly connected with the feed screw 68 at a short distance from the piston 14. Between the piston and this body is interposed a coil spring 106, which spring has an end 108 attached to the piston 14 and its end 110 attached to the body 104.

The spring housing 74 extends sufficiently far beyond the cap 58 to provide a convenient grip. Knurled or ornamented surfaces 112 are provided on the outer face of the barrel 12.

The tubular parts, the tip 52 and the spring housing 74 may be formed of any suitable material, preferably plastics. When plastics are employed, the piston 14 may be conveniently fitted for frictional connection with the tube 12.

In operation, the valve end 72 is maintained in yielding engagement with the valve seat 28. To dispense material from the tube 12, the spring housing 74 is rotated relatively to the cap 58, the latter being fixedly connected with the barrel 44 so far as this operation is concerned. Such rotation of the spring housing 74 causes the body 104 to move longitudinally of the feed screw 68 and forces the feed screw 68 upwardly against the tension of the spring 98. Such movement of the feed screw lifts the valve end 70 off the seat 28 and permits the material in the tube 12 to extrude from the nozzle 22. The feed continues until the spring 98 has again seated the valve 16. My invention provides a dispensing container wherein a simple and easily performed rotative movement of the spring housing 74 initiates the dispensing operation. The amount of material extruded is easily controlled through regulation of the amount of rotation imparted to the spring housing. The tube 12 is easily removed for substitution of a new tube. While the nozzle 22 extends some distance inside the tube 12, the piston 14 is so contoured as to fit over the nozzle and extrude the material from the space 30 in the substantially emptied condition of the tube 12.

Without further elaboration, the foregoing will so fully explain my invention, that others may, by applying current knowledge, readily adapt the same for use under various conditions of service.

I claim:

1. A device of the type described comprising a plastic material containing tube having a nozzle at one end, said nozzle being provided with a

valve seat, a barrel enclosing said tube and constituting a mount therefor, a piston slidably in said tube, a feed screw arranged longitudinally in said tube and extending loosely through said piston, a body threadedly connected with said feed screw, resilient means connecting the body and the piston, an actuating means mounted for rotation relatively to said barrel and said tube, said feed screw being connected for rotation with 10 said actuating means but slidably connected therewith for movement longitudinally of the tube and the barrel, and resilient means interposed between said actuating means and said feed screw to urge the latter against said seat 15 when lifted therefrom through rotation of said actuating means and compression of said last mentioned resilient means.

2. The invention described in claim 1 wherein said barrel is provided with shoulder means engaging said tube to fixedly relate the latter inside the barrel, and means threadedly connected with the barrel to secure one of said shoulder means and constituting a mount for said actuating means.

25 3. The invention described in claim 1 wherein shoulder means are provided in said barrel for engagement with end formations on said tube, a cap threadedly connected with one end of said barrel for securing one of said shoulder means, 30 said cap having a bore and said actuating means being rotatably mounted in said bore and shaped to provide a housing for said last mentioned resilient means.

4. The invention described in claim 1 wherein said nozzle includes a bore for loosely receiving one end of said feed screw, said valve seat being located in said bore, said nozzle being provided with a port placing said bore in communication with the interior of said tube when said feed screw is lifted off said valve seat.

5. The invention described in claim 1 wherein said first mentioned resilient means comprises a coil spring having one end attached to said body and its other end attached to said piston, and in 45 which said actuated means comprises a housing for said second mentioned resilient means.

6. The invention described in claim 1 wherein said piston and said nozzle are respectively provided with rupturable end formations constituting closures for the piston and the nozzle.

7. The invention described in claim 1 wherein said barrel is provided with a cap threadedly connected therewith, said cap having a bore coaxial with said tube, said actuating means comprising a second tube rotatably supported in said bore, said last mentioned resilient means being housed in said second tube and having one end abutting an end of the second tube and its other end connected with said feed screw, said 60 second tube being slotted, and a key means on said feed screw slidably guided in the slot in the second tube, said slot extending longitudinally of the second tube.

HUGH F. KIRKWOOD.
